INVENTOR.
Joseph M. Angeletti

UNITED STATES PATENT OFFICE.

JOSEPH M. ANGELETTI, OF NEW YORK, N. Y.

TYPEWRITER.

Application filed December 14, 1925. Serial No. 75,322.

The invention relates to improvements in typewriting machines of the portable type and more particularly to the type-action and its supporting frame, and the main object of 5 the invention is to provide a visible or front strike type-action for a machine of the above character composed mainly of two unitary parts, namely a vertically actuated approximately L shaped key-bar adapted to actuate a 10 pivoted type-carrying bar for selectively causing one of its characters to print upon a work sheet held by a platen.

Another object of the invention is to provide said type-action with an associated supporting casing or frame composed of few 15 simple parts functioning also as the inclosing case for said machine, and which is not required to be separated therefrom during the operation of the machine.

20 A further object is to so construct said type-action and its supporting casing of few simple and efficient parts thereby possibilitating the manufacture of a more economic, durable, and lighter portable typewriter than 25 possible with more complicated and expensive type-actions of other typewriters.

With the above and other objects in view the invention will be hereinafter more fully described with reference to the accompanying 30 drawing forming a part of this specification, and will then be pointed out in the claims at the end of the description.

In the drawings:

Fig. 1 is a top plan view of the device embodying my invention.

Fig. 2 is a longitudinal side view of Fig. 1 showing more clearly the parts composing the front strike type-action and its associated supporting casing embodying my invention.

Fig. 3 is a side elevation of the supporting casing, showing same in a closed position, and

Fig. 4 is a detailed vertical side view of the type-bar used in said type-action.

Referring now to the parts composing the device, 1 denotes the base plate of the associated supporting casing for said type-action, said base having side walls 1^A and 1^B, a front wall 1^C and an open base extension 1^D. A middle plate 2 having rows of openings or slots 2^A. A top plate 3 having an end collar 3^A and rows of openings or slots 3^B which are in register with that of plate 2, as at Figs. 1 and 2.

Plates 2 and 3 may be variously assembled

on the above mentioned base 1. As shown, I provide a plurality of vertical rod supports 4 having at one or both ends threaded sockets 4^A, said supports linking said plates by means of suitable openings 5, and in order to keep said plates in spaced positions I provide a plurality of spacing sleeves 6 and 7, in which are inserted supports 4 between the plates, forming the casing into two interiorly spaced compartments 8 and 9, when said supports are fastened by means of screws 10, as at Figs. 1 and 2. It is obvious that one of the pair of spacing sleeves on each support 4 could be replaced by forming a shoulder on the support itself if desired, as it will serve the same purpose, and that the rows of openings or slots on both the middle and top plates may be in a straight row formation instead of curved as illustrated, the idea of so illustrating said rows of slots in curved formation was to make unnecessary an angular shaping of the key-bars which will be hereinafter described, so that to add to its economic construction, being one of the main objects of 80 this invention.

The printing mechanism or type-action consists principally of a plurality of approximately L shaped key-bars 11, having their vertical stem or arm vertically movable in openings 2^A and 3^B of plates 2 and 3, as at Figs. 1 and 2. The horizontal arm of said key-bars is downwardly curved at 11^A, and in order to return the key-bars to their normal operative position, I provide springs 12 which I prefer to insert on the vertical arm of the key-bars and acted upon by pins 13, compressing said springs against plate 2, when the key-bars are depressed from their provided key-caps 14, as at Fig. 2. A plurality of type-bars 15, having a horizontal projection 15^A, with a longitudinal slot 15^B, and a pivotal opening 15^C below said projection, while between the projection and pivotal opening, is a forwardly disposed approximately U shaped recess 15^D adapted to receive a universal bar A, and above said projection is a folded or doubled up body part 15^E forming a front wedge 15^F, adapted to actuate a pair of longitudinally slidable bars B B, for a ribbon feed mechanism. At the uppermost end of said type-bars is a type-block 16, which may contain one or more characters and as illustrated are indicated by 17 and 18, as more clearly seen in Fig. 4. Said type-bars are all arranged in a curved row pivotally held spaced by a common pivot rod 19, which

105

110

is curved in conformity with the row and having bearings at 20 on provided lugs of a segment 21, as at Fig. 2. Key-bars 11 are pivotally connected individually to type-bars 15, by means of headed pins 22 through the longitudinal slots or openings 15^b and fastened at the furthermost horizontal end of the curved arm 11^a of said key-bars, the curve on said arm serving to keep it from contacting with said segment 21 during the actuation of the key- and type-bars when one of the characters carried by the bars is caused to print upon a work sheet held by a platen C. It is obvious that some of the type-bars in proximity of their type-blocks require to be angularly shaped so that to allow each type-bar to strike a common printing point of platen C, when actuated upon by said key-bars.

As a means for closing the open base 1^D and top of said casing, when the machine is not in operation, and in order to protect its exteriorly projecting parts when the machine is wanted to be carried around, I provide a cover section 23, having upwardly bent ends 25 or ears 23^A hinged at 23^B to the furthermost horizontal ends of said open base 1^D, so that if desired the section may be conveniently swung toward or from the base of said casing, as well as toward and from its open end to form a rear wall and right and left wall portions to said open base closing the lateral passageways of platen B, when the machine is not in operation. A second cover section 24, having front, right and left walls is hinged at 23^C on the bent ends or ears 23^A of cover section 23, as at Figs. 1, 2, and 3. Cover section 24, thus is also adapted to be swung toward and from the base of said casing either separately or with the first mentioned cover section, as well as adapted to cover the top of said casing to which it may be conveniently secured by means of a suitable lock 25, mounted on the front wall 1^C of the casing and having a cooperating part 25^A mounted on the front wall of said cover section 24, as at Fig. 1. A handle 26, may be mounted on the front wall 1^C of the casing for convenience in carrying the machine around.

The above described type-action operates as follows:

At the depression of a key-bar 11, from its cap 14, a type-bar 15, moves toward printing position, the horizontal projection 15^a of this bar depresses universal bar A, for escapement operation, and before the type-bar strikes the printing point, universal bar A, returns to normal position by entering recess 15^D of the bar; in the same instant, wedge 15^E of the type-bars entering inlet D, which is formed by the bent ends of slidable bars B B, the latter being in a movable coacting position, causes the slidable bars to move longitudinally in opposite directions, thereby actuating a ribbon feed mechanism, when the type-bar retreats from printing position, the

longitudinally slidable bars return to their normal positions.

In the foregoing description, I have embodied the preferred form of my invention, but I do not wish to be understood as limiting myself thereto as I am aware that modification may be made therein without departing from the principle or sacrificing any of the advantages of this invention, therefore I reserve to myself the right to make such changes as fairly fall within the scope of the claims.

Having thus described my invention, I claim as new and desire to secure by Letters Patent:

1. In a typewriter the combination with vertically pivoted type-bars, of a casing having an open end and an open base extension, of a plate having curved rows of slots all pointing to a common center and secured between the top and base plate of the casing to form two interiorly spaced compartments, the top plate having curved rows of slots communicating with the rows of the first mentioned slotted plate, the said top plate having a longitudinally disposed curved collar end situated at approximately the center above said open end, and a plurality of key-actuated-bars vertically movable through the slots of said plates and adapted to actuate said plurality of vertically pivoted type-carrying-bars, the latter having head support in said curved collar end.

2. In a typewriter the combination with a pivoted type-bar, of a vertically actuated key-bar consisting of a horizontal portion directly pivoted at its forward end to said type-bar, a vertical portion extending upwardly from the rear end of the first mentioned portion and having a finger key at its apex, and guiding means for said vertical portion confining the same to vertical reciprocation whereby said type-bar will be actuated arcuately only.

3. In combination with the supporting means in a typewriter, of a plurality of approximately L shaped key-bars adapted to be vertically actuated through said supporting means, the horizontal arm of the key-bars being downwardly curved and a plurality of pivotally supported type-carrying-bars individually and directly pivoted to the horizontal arm of said key-bars for being moved toward and from the printing point of a platen.

4. In a typewriter the combination of a casing having an open end and an open base extension horizontally projecting therefrom, of a cover section hinged longitudinally at the furthermost horizontal edge of said base extension and adapted to be swung toward and from the underside of said base, as well as toward and from the open end of said casing forming right, left and rear walls to said open base extension when said cover is in a closed position, and a second cover section hinged longitudinally to the first mentioned hinged cover section and adapted to close the top of

said casing as well as swingable under the base thereof.

5. In a typewriter the combination of a casing having an open end and an open base extension horizontally projecting therefrom, of an H shaped plate longitudinally hinged to the furthermost end of said base extension so as to be swung toward and from said open end to form a rear wall, and right and left wall portions at the open base extension, as well as reversible to the underside of said open base extension. 75

6. In combination with a typewriter of a casing having an open end, and an open base extension horizontally projecting therefrom, of an approximately H shaped wall-cover-section longitudinally hinged to the furthermost end of the open base extension for being swung toward and from the open end of the casing to close the side walls of said open base, as well as toward and from the underside thereof, of a top cover section longitudinally hinged to the furthermost horizontal end of the hinged wall cover section for being swung 80 toward and from the top of the casing as well as reversible under the bottom thereof.

7. In a typewriter the combination of a casing having an open end and an open base extension protruding horizontally therefrom, of a cover section hinged to the immediate end of said open base extension so as to be swung towards and from said open end, as well as towards and from the underside of said base extension, of a second cover section 95 having front, right, left and top walls hinged to the immediate end of the first mentioned hinged cover section for being swung towards and from the top of the casing as well as towards and from the base thereof, and a lock for securing said sectionally hinged cover to a closed portion.

8. In a typewriter the combination of a casing having an open end top and base plates and an open base extension, of a plate having 100 curved rows of slots all pointing to a common center and mounted between the top and base plate of the casing, the top plate having rows of slots communicating with the rows of the first mentioned slotted plate, said top plate 105 having a curved collar end centered in proximity of said open end of a plurality of approximately L shaped key-bars vertically movable through the slots of said plates, and means for returning said key-bars to their normally supported position after having been vertically depressed, said means consisting of a spring engageable by the vertical arm of said key-bars during their vertical movement. 110

9. In a typewriter the combination of a casing having an open end wall and an open base extension, a plate having rows of slots mounted between the top and base plate of the casing to form two interiorly spaced compartments, the top plate having rows of slots

communicating with the rows of the first mention slotted plate, of a plurality of approximately L shaped key-bars vertically movable through said rows of slots and means for returnning said key-bars to their normally supported position, said means consisting of a compression spring involuting each vertical arm of said key-bars, and means on the bars adapted to engage said springs to compress same against the first mentioned slotted plate. 75

10. In a typewriter the combination with a plurality of type-bars pivotally supported by a segment, a plurality of vertically actuated key-bars having each a horizontal portion the forward end of which being downwardly curved and directly pivoted individually to said type-bars, said curved end adapted to overlap said segment, a vertical portion on said key-bars extending upwardly from the rear end of said horizontal portion, and guiding means for said vertical portion confining the same to vertical reciprocation, for individually actuating said type-bars arcuately only. 85

11. In a typewriter the combination of a plurality of vertically actuated approximately L shaped key-bars the horizontal arm of which having each a longitudinally supported pivot or pin, a plurality of type-bars 95 pivotally supported and having each a forward projection with a horizontally disposed slot adapted to admit the pin or pivot of said key-bars for being individually actuated toward and from the printing point of a platen. 100

12. In combination with a plurality of vertically movable key-bars in a typewriter, of a plurality of pivotally supported types carrying-bars having a forwardly projecting body part horizontally slotted and individually pivoted to said key-bars for being moved to strike the printing point of a platen, and a forwardly disposed notch on each of the type-bars between its pivoted end and forward projection to receive a universal bar. 105

13. In a typewriter the combination of a frame having a plurality of key-actuated bars supported therein, of a plurality of pivotally supported type-bars having a forwardly projecting and horizontally slotted body part pivotally connected to said key-bars for being moved toward and from the printing point of a platen, said type-bars having a forwardly disposed approximately U shaped recess between the pivot end and projecting body to receive a universal bar. 115 120

14. In a typewriter, a type-bar having a fulcrumed end, a horizontally slotted projection above said fulcrumed end, and a forwardly disposed approximately U shaped recess between the fulcrumed end and projection to receive a universal bar. 125

15. In a typewriter, a vertically actuated key-bar consisting of a vertical arm with a finger piece or key, and a horizontal arm member having a downwardly curved end 130

with a longitudinally supported pivot adapted to pivotally engage a type-bar.

16. In combination in a typewriter having a casing with an open end wall, of a separative plate mounted between the top and base plates of said casing forming the casing into two interiorly spaced compartments, and means for removably securing said separative plate in its spaced position, said means consisting of a plurality of vertical supports fastened at one end to either the base or top plate of the casing, said supports having each a hollow or separative sleeve between the fastened end and separative plate, the upper ends of said supports driven in borings of the separative plate through a second hollow or separative sleeve, the second end of said supports having each a threaded socket, and screws driven through borings of the adjacent plate and threaded in said sockets.

17. In a typewriter the combination of a type-bar having a fulcrumed end, a horizontally slotted projection above said fulcrumed end, a forwardly disposed recess be-

tween said fulcrumed end and projection to receive a universal bar, a type-block on the type-bar, and a folded body part on said type-bar, in proximity of said type-block to increase the longitudinal movement of a pair of longitudinally slidable bars during the entrance of said type-bars between said longitudinally slidable bars.

18. In a typewriter the combination of a plurality of type-bars having a fulcrumed end, a horizontally slotted projection above said fulcrumed end, a forwardly disposed notch between said fulcrumed end and projection to receive a universal bar, type-blocks on said type-bars, and a folded body part on said type-bars in proximity of said type-blocks doubling up the thickness of said portion of the type-bars for increasing the longitudinal movement of a pair of longitudinally slidable bars during the transiency of said type-bars between said longitudinally slidable bars.

JOSEPH M. ANGELETTI.
